GEORGES JEAN MARIE DARRIEUS, OF PARIS, FRANCE, ASSIGNOR TO SOCIÉTÉ ANONYME
POUR L'EXPLOITATION DES PROCÉDÉS MAURICE LEBLANC-VICKERS, OF PARIS,
FRANCE

WIND MOTOR

Application filed June 22, 1928, Serial No. 297,520, and in France June 27, 1927.

This invention relates to fluid motors and more particularly to propeller blades therefor.

The use of a fluid such as the wind for the production of electric energy involves many problems. The ideal for which all have been striving is apparatus therefor having completely automatic operation, and in which, successful operation is not hindered by needless multiplicity of parts. But, one of the difficulties limiting this ideal has arisen from the need of some additional means compensating for the resultant increase of speed and torque produced by a high wind velocity.

In other words, since the velocity of the actuating fluid such as the wind for a given day's operation is seldom of constant value, and varies between certain high and low limits, it follows that some means must be provided that is sensitive to these variations in the wind velocity and that will withhold and resist an increase of speed of the blades or vanes of a fluid motor. Apparatus has been designed for this purpose.

Some have provided an impeller having propeller blades, vane wheels or the like, with a tail vane or auxiliary directing vane wheel pivoted thereto. For larger size impellers, the blades or vane wheel were, themselves, often pivotally positioned so that they could be partially or wholly withdrawn from the thrust of the wind when its velocity exceeded a given amount. This was accomplished by means of springs compressed by the increased thrust of the actuating fluid.

Another suggested solution consisted in providing the impeller with auxiliary surfaces that were brought into opposition to forward thrust of the fluid, as by means of centrifugal force, at a certain blade or vane speed. This apparatus is often termed an absorption brake of the type called "Colonel Renard's vane wheel."

But previous to the present invention, no one has provided an impeller having rigidly mounted blades, vane wheels or the like, that of themselves, without the aid of auxiliary equipment or attachments, compensate for, and suppress unfavorable results produced

by an increase of fluid velocity above the normal variations of operation.

It has been one object of my invention to provide an impeller that without the aid of auxiliary apparatus, can be designed to automatically operate below a certain predetermined speed.

Another object of my invention has been to provide an impeller that without the aid of auxiliary apparatus, can be designed to keep within certain limits of torque even though the fluid velocity suddenly increases.

Still another object of my invention has been to provide impeller blades having substantially like angles of incidence along their entire length or radius.

A further object of my invention has been to provide an impeller than can be designed to operate at a substantially constant speed, and to produce a substantially constant torque, governed by the thrust impressed upon its blades for a given fluid or wind velocity.

A still further object of my invention has been to provide an impeller having blades of extreme narrowness but of suitable strength and tangential rigidity.

A still further object of my invention has been to provide a more simple, positive, and efficient impeller blade.

These and many other objects of this invention will appear to those skilled in the art from the following description taken in conjunction with the accompanying drawings in which:—

Fig. 1 is a plot of propeller characteristic curves used in the design of my invention.

Fig. 2 is a side view of a device constructed in accordance with a form of my invention.

Fig. 3 is a side view of a device constructed in accordance with another form of my invention.

Fig. 4 is a perspective view of a further embodiment of my invention.

Fig. 5 is a sectional view of member 15 on line V—V of Fig. 3; and

Fig. 6 shows sectional views on lines VI—VI (a) and VI—VI (b) of member 22 of Fig. 4.

Although a preferred form of my invention

- tion is shown in Fig. 4, yet impellers 10, such as shown in Figs. 2 and 3 may be employed, provided that the requirements of torque, speed, and strength are within certain limits.
- 5 The impellers 10 shown in Figs. 2 and 3 include a plurality of propeller blades or vanes 11, rigidly secured to a common axis 13. The aero-foils 12 of the blade 11 overlap each other substantially in the direction of the axis 13, so as to provide a light but strong compound girder blade. Structure 14 and braces 15, both stream lined to reduce resistance to forward movement may be provided to strengthen the blade 11. Fig. 5 illustrates 15 the stream line form of the brace 15; and, the structure 14 has a similar stream line section, differing from the brace 15 only in relative width.

But, the preferred form of my invention 20 shown in Fig. 4, is designed to meet substantially all the torque, speed, dimension, and strength requirements of normal field service. The operating basis for these requirements is hereafter set forth.

25 In cases where the extreme narrowness of the blades would induce fear of an insufficient strength in the tangential direction, the several aero-foils may be staggered with respect to each other in this tangential direction so as to constitute a frame of a sort of pylon having a great moment of inertia in all directions and substantially braced with respect to shearing forces (see Fig. 4). The blade 21 in Fig. 4 can be employed in place 30 of the blades 11 of Figs. 2 and 3 in connection with the impeller construction shown. Although any suitable type of impeller and drive mechanism can be employed, yet, it follows that the peculiar construction of the 35 blade 21 needs specific description here.

In the preferred embodiment of a propeller blade 21, to which the principles of my invention are particularly adaptable, a plurality of stream line aero-foils 22 have been 40 provided, each of the aero-foils 22 at one end 24 merges with the others to form the apex of a pylon; from the apex 24, each aerofoil slopes outward towards its supporting end, where it is rigidly and securely fixed 45 to a common axis 26 in any suitable manner. Fig. 6 shows the stream line construction of the aerofoil 22.

The axis 26 may be provided with slots 27 of relatively shallow depth for receiving each 50 supporting end of the blade 21. In order to reinforce the blade 21, a plurality of shelves or stays 28 are positioned to be clamped between the plurality of aerofoils 22, substantially parallel to the blade axis 26, for tying them together at points along their length. To further reinforce against 55 shearing, centrifugal, twisting and other forces inherent in propeller blade action, oblique tie structure 29 of wire or other suitable material is rigidly secured so as to cross-

brace one aero-foil 22 with respect to the others of a given blade along the length thereof in a manner shown in Fig. 4.

The wind motor 10, itself, including the blades 21 and their common axis 26, may be 70 positioned as shown in Figs. 2 and 3, or in any other suitable manner, so that the common axis 26 may rotate about a stationary support 9 or the like and that a generator or the like can be positioned to rotate with 75 the axis 26 by the employment of suitable gearing, belt, shaft or the like (not shown).

In addition, the vanes or blades of the impeller or wind mill shown in Figs. 2, 3 and 80 4 are inclined in the direction of the flow of the wind or actuating fluid as indicated by the arrows, so that under the action of centrifugal force, these vanes or blades being of relatively thin section, tend to straighten themselves, and to thus counterbalance the 85 shearing and twisting forces exerted by the wind.

The wind motor system which is the subject of this invention, is based upon the following technical considerations. Sections 90 finely streamlined and with great transversal elongation employed in aviation have the property that, as long as the angle of incidence with respect to the chord of the section does not exceed a limit of a few degrees, the thrust of the fluid varies nearly proportional to this angle incidence and moreover remains almost exactly normal or perpendicular, not to the chord of the section, but to the direction of the relative speed. 95 On the contrary, beyond a certain critical angle of incidence, the drag or resistance to blade advancement, that is to say the component of the force of the fluid parallel to, but in opposite direction to, the relative speed 100 of the blade section, increases rapidly, so that a vector representing the resultant blade actuating thrust, departs slightly towards the chord of the blade section, from its normal or perpendicular position with respect to 105 the relative speed. From this instant, the thrust of the blade section and its vector component in any direction whatever now appreciably depend on nothing except the square of the relative speed of this section 110 with respect to the speed of its actuating fluid.

The wind motor system of the present invention includes wings, blades or vanes of 115 very fine section, that is to say, having a very small ratio of drag for a given thrust of the actuating fluid.

Due to this feature, the blades can be very little inclined to the plane of rotation, that is, they can have a very small ratio of pitch to diameter, without a corresponding reduction of the tangential or useful component of the actuating fluid thrust and an increase 120 of the drag. This ratio of pitch to diameter 125

may be 1:3; and, the purpose of employing such a ratio will be explained.

In the present invention it is necessary that the tangential or useful speed of the blade should be maintained at a value higher than the velocity of the actuating fluid, and, for the form of a blade shown in Fig. 4 which has been designed to meet normal working conditions, the ratio should be substantially

10 to 1. In other words, the ratio of the tangential speed of the blades to the absolute velocity of the wind should equal 10 to 1. To accomplish this it is necessary to provide blades of very fine, stream-line section and having a high ratio of surface sweep to blade surface; this latter ratio is substantially proportional to the ratio of the tangential velocity to the absolute velocity of the wind. But, the difficulty arises in the design and construction of a propeller blade that has the necessary properties of strength even though of fine, stream-line section; to accomplish this purpose, the inventor has provided a blade comprising three aerofoils formed into a sort of pylon, as before explained.

The ratio of 10 to 1 is employed in order that the relative speed of the blades will not substantially depend upon the velocity of the actuating fluid within the widest limits of variation of the latter anticipated under normal operation conditions. Of course, the speed of rotation of the blades must remain substantially constant to ensure the above condition. But, the latter condition is maintained, since, a given increase in the wind velocity will cause a transcendence of the critical value of a chosen working angle of incidence that corresponds to a given maximum thrust of fluid; and this transcendence gives rise to the appearance of an important drag as the torque or couple and the power stop increase; and also at this point the stream lines of the actuating fluid are then separated.

Thus, it follows, a blade having a suitable angle of incidence can be provided by keeping the ratio of surface sweep to surface of blades at substantially 10 to 1. This ratio, founded on the stream line section of the blade, lays the foundation for a high tangential speed of the blade. In other words, the ratio of the tangential speed of blade to absolute velocity of actuating fluid will also be substantially 10 to 1. Employing the above ratios, it has been found that a suitable angle of incidence having a desired point will be provided when the ratio of blade pitch to diameter is taken as 1 to 3. And further, in his choice of blade sections and of their position along the radius of the common axis, the inventor has taken similar sections having widths inversely proportional to the relative speed of the blades with respect to their actuating fluid; or, after a certain distance from the axis of rotation, nearly in inverse proportion to their corresponding radius or length,

so that the angle of incidence for each portion of the blade along its entire length of radius is kept at a substantially constant value, and that the transcendence thereof caused by a high velocity of the actuating fluid will occur simultaneously along the entire radius or length of each blade. This gives to one of the edges of the blade the shape of a hyperbola if the other edge is straight.

Another reason for keeping the ratio of pitch to diameter of a small value, say 1:3, is, in order that the actuating fluid thrust shall have a relatively large value in respect to the drag, and that the wind motor shall have a high efficiency.

In Fig. 1 is shown a diagram of a system of co-ordinates having angular speed as abscissa and the couple or torque as ordinates. A set of curves have been plotted, each corresponding to a certain definite value of the velocity of the wind.

The general path of each of the curves for a certain velocity of the wind, at first increases for a given increase of angular velocity of speed of the blades, and then, decreases. This condition follows when the ratio of the pitch to the diameter and the ratio of the surface of the blades to the air surface swept is kept at a very small value. According to the present invention such conditions are chosen so that all the curves representing a certain value of the velocity of the wind touch each other along a common envelope in the neighborhood of which they are very close together. In mathematical language this result is represented by the ratio

$$\frac{dT}{dV} = 0,$$

for the points of contact of these curves with their envelope. "T" represents the torque or couple and "V" the velocity of the actuating fluid, and "d" represents the derivative. In other words, the curves are chosen so that a straight line, indicated by "e" in Fig. 1, can be drawn through their points of contact, and further, so that the angular speed of each portion of the blade is such that the equation of

$$\frac{T_1}{T_2} = \frac{V_1}{V_2}$$

equals a constant. Where: T_1 represents the torque at a point of contact of the curve "e" for a given velocity of the actuating fluid represented as V_1 , and T_2 represents the torque at a point of contact on a curve for a given velocity of fluid represented as V_2 .

By keeping the angle of incidence of every portion of the blade along its entire length at a given value, when the velocity of the wind exceeds a value corresponding to the normal working speed of the blade, the critical angle of incidence is exceeded almost simultaneously at practically all points of the radius or length thereof. Thus, there is a

sudden increase of drag that for these sections separates the stream lines at the back of the blade or wing and compensates for the slight increase of thrust. Of course, the sections nearer the axis are more sensitive to an increase of the velocity of the wind owing to their less tangential speed, but as before explained, the choice of the width and pitch of the blade portions has offset the effect thereof upon the chosen critical angle of incidence.

Further, still in accordance with the invention, another safe guard of constancy of the speed beyond the point of normal working is obtained by giving to the electric generator a suitable characteristic; illustrated as " e " (see Fig. 1), according to which, the resisting couple or torque will increase more rapidly as the function of the speed since it does not correspond to the slope e of the envelope at its point of operation. This characteristic crosses the envelope in the direction shown in Fig. 1 and may represent a synchronous alternator running in parallel on a supply system and therefore at constant speed, or the shunt characteristic of an asynchronous machine with slight slippage. The invention is not limited to these particular constructions (see Figs. 2, 3 and 4), but extends to any method or combination of known elements of stream line section which, by suitable choice of speed and number of blades, of their relative width, pitch, etc., produces the particular characteristics of working which has heretofore been described.

What I claim is:

1. A fluid motor having a plurality of blades mounted on a common hub, each of said blades having the form of a pylon of triangular section, said pylon consisting of three aerofoils rigidly secured to the hub.

2. A fluid motor substantially as specified in claim 1 whose blades are bent in the direction of flow of the actuating fluid, so that the centrifugal force of the blades of said motor when rotating will tend to counterbalance the shearing and twisting forces exerted by the actuating fluid.

3. The combination in a fluid motor of a rotating hub, a plurality of radially extending blades of tapered profile rigidly mounted on said hub, said blades being formed so that the pitch at every point of the radius thereof will have a ratio of not more than 1 to 3 to the diameter of the circle of fluid swept out by the blades when rotating on their hub.

4. The combination in a fluid motor, of a rotating hub, a plurality of radially extending blades of tapered profile rigidly mounted on said hub, the fluid area swept over in the rotation of said blades having a ratio of not more than 10 to 1 to the surface area of the said blades, so that the tangential speed of said blades will be greater than the velocity of the actuating fluid.

5. In a fluid motor, the combination of a plurality of blades mounted on a common hub, each of said blades including three aerofoils rigidly secured to said hub and whose widths decrease for portions of increasing distance from the hub, said aerofoils merging at their extending ends to form a blade having the form of a pylon of triangular section.

6. In a fluid motor, the combination of a plurality of blades mounted on a common hub, each of said blades having the form of a pylon of triangular section, said pylon including a plurality of aerofoils rigidly secured to the hub, the surface area of said aerofoils of the blades having a ratio of not more than 1 to 10 to the area swept out by said aerofoils during rotation of the blades, so that a high ratio of tangential speed of the blades to the velocity of the actuating fluid will be maintained.

7. A fluid motor having a rotating hub and a plurality of blades mounted thereon, each of said blades having the form of a pylon of triangular section, said pylon including a plurality of aerofoils rigidly secured to the hub, stays disposed between said aerofoils for tying them together at portions along their length, and oblique ties for cross bracing one aerofoil with respect to each of the others along the length of each of said blades.

8. In a fluid motor, the combination of a plurality of blades mounted on a common hub, each of said blades having the form of a pylon of triangular section, said pylon including three aerofoils rigidly secured to the hub, each of said aerofoils having a pitch which decreases, and a width which decreases with portions of increasing distance from the hub thereof, so that blades will be provided having a certain definite critical angle of incidence upon the transcendence of which the stream lines of the actuating fluid will be separated for preventing further increase of the rotative speed of the blades, and so that the angle of incidence will be transcended simultaneously along the entire length of the blades.

9. A fluid motor having a plurality of blades mounted on a common hub, each of said blades having the form of a pylon of triangular section, said pylon including a plurality of aerofoils rigidly secured to the hub and merging at one end to form a common apex.

10. A fluid motor having a plurality of blades mounted on a common hub, each of said blades having the form of a pylon of triangular section, said pylon including a plurality of aerofoils rigidly secured to the hub, and oblique ties for cross bracing one aerofoil with respect to each of the others along the length of each of said blades.

11. A fluid motor having a plurality of

blades mounted on a common hub, each of said blades having the form of a pylon of triangular section, said pylon including a plurality of aerofoils rigidly secured to the hub, stays disposed between said aerofoils for tying them together at portions along their length.

In testimony whereof I have signed my name to this specification at Paris, France, this 8th day of June, 1928.

GEORGES JEAN MARIE DARRIEUS.
